(74) Attorney, Agent, or Firm — Preston Smirman;
Smirman IP Law, PLLC

(57) **CLAIM**

I claim the ornamental design for a ship, as shown and described.

DESCRIPTION

FIG. 1 is a rear view of my design for a ship;

FIG. 2 is a bottom view of my design for a ship;

FIG. 3 is a front perspective view of my design for a ship;

FIG. 4 is a left perspective view of my design for a ship with the missile niches in the closed position;

FIG. 5 is a left perspective view of my design for a ship with the missile niches in the open position;

FIG. 6 is a right perspective view of my design for a ship with the missile niches in the closed position;

FIG. 7 is a right perspective view of my design for a ship with the missile niches in the open position;

FIG. 8 is a top view of my design for a ship;

FIG. 9 is a left elevational view of my design for a ship with the missile niches in the open position; and,

FIG. 10 is a right elevational view of my design for a ship with the missile niches in the open position.

1 Claim, 10 Drawing Sheets
